(57) **CLAIM**

The ornamental design for an oral care accessory, as shown and described.

DESCRIPTION

FIG. 1 is a front elevation view of an oral care accessory showing my new design with removal strips separated from a package for clarity;

FIG. 2 is a rear elevation view thereof;

FIG. 3 is a right elevation view thereof, the opposite side being a mirror image of the shown;

FIG. 4 is a top plan view thereof;

FIG. 5 is a bottom plan view thereof; and,

FIG. 6 is an isometric view thereof.
